UNITED STATES PATENT OFFICE.

DENNIS PARKS, OF ST. LOUIS, MISSOURI.

VICE.

973,381.

Specification of Letters Patent. Patented Oct. 18, 1910.

Application filed July 6, 1909. Serial No. 506,037.

To all whom it may concern:

Be it known that I, DENNIS PARKS, a citizen of the United States, residing in the city of St. Louis and State of Missouri, have invented new and useful Improvements in Vises, of which the following is a specification.

This invention relates to an automatically operating vise intended more especially for use in connection with boring implements, such as drills, but being useful in various applications where a body is to be gripped and held stationary while being operated upon.

In the accompanying drawing Figure 1 is a view in side elevation of my improved vise, certain parts of a drill being shown in dotted lines to illustrate the method of use of the device. Fig. 2 is a top plan view of the vise on an enlarged scale. Fig. 3 is substantially a transverse sectional view taken on a line at one side of the device, jaws of the vise being shown in elevation, and certain guide pins being shown in section, and Fig. 4 is a sectional view on the line 4—4 of Fig. 3.

The device comprises a base 1, having on opposite sides elongated or other apertures 2, by means of which it may be suitably secured on a suitable support, such as the bed 3 of a drill press. Rising from the base 1, and preferably, though not necessarily, formed integral therewith, are two side members 4, which with the base form the frame of the machine. Each of the side members 4 has in its upper side a large V-shaped recess which extends from opposite ends of each side to the middle of the side member, and thus provides two inclined ways 5 on which the jaws 6 of the vise are adapted to slide. Each of the side members 4 is provided near the edge of each of the ways 5 with a fixed stud 7 which projects inward a short distance beyond the inner face of the side members as shown in Fig. 4. Each of the jaws 6 is preferably provided with a series of stepped and interdental recesses 8 to accommodate, and form gripping surfaces for, various sizes of objects. The jaws rest upon the inclined ways 5, and have a central reduced portion forming a rib 9 which fits snugly, but so as not to bind, in the space between the side members 4. Each of these ribs is provided on opposite sides with a longitudinally-disposed groove 10, each of which receives a stud 7 by means of

which the jaws are guided to move in right lines, the said studs preferably having straight parallel sides to better perform the guiding function, as will be understood.

60

11 indicates a member which I term a cradle, which consists of two semicircular sides 12 united at their upper ends by cross-pieces 13.

14 indicates a lever which is pivoted at 65 its inner end, as indicated at 15, between the side members 4, and intermediate its ends between the sides 12 of the cradle 11, as indicated at 16. The pivot 16 is located centrally of the cradle 11, as respects dis-

70

stance from its ends, and by raising or lowering the lever 14 the cradle 11 may be raised or lowered. Each of the sides 12 of the cradle is recessed in its upper portion in a manner to provide a flat base 17 extending 75 parallel with the base 1. Each of the jaws

6

is provided at its lower end with a flat surface 18 which normally rests upon the bases 17 of the cradle. Projecting rear- 80

wardly and centrally from each of the jaws

6

is an arm 19, which arms project between the sides 12 of the cradle and are adapted to be engaged on their upper sides by the cross-pieces 13 of the cradle. When the cradle 11 is elevated by raising the lever 14 85

90

the jaws 6 will likewise be raised and also caused to diverge. As soon as the lever 14 is released the jaws will tend to slide down the ways 5 and consequently to approach each other, this action being automatic and effected by the force of gravity. A body, 95

100

such as indicated in dotted lines by 20, having been placed between the jaws at a proper height thereon, according to its size, when the lever 14 is released the jaws will auto-

105

matically grip the object and the harder the object is pressed upon, as in being bored by a drill 21, the firmer the jaws will grip the body. If, however, from the nature or shape of the body to be gripped by the vise, 110

105

or from lack of pressure upon the body, as when the drill 21 has passed through it, or when the drill is being withdrawn, the jaws do not grip the body with sufficient firmness to hold it from turning or other movement, the operator may increase the grip of the jaws by pressing down on the lever 14, in

110

which operation the cross-pieces 13 will engage the upper sides of the arms 19, and thereby press the jaws more firmly toward each other as will be understood.

The parts of the vise are of metal. The

base and side members, the cradle, and each of the jaws, are respectively made as integral structures.

I claim:

- 5 1. A vise comprising a base, a frame thereon affording oppositely-disposed inclined ways converging toward said base, and a jaw mounted to slide on each of said ways, said jaws, when raised, being free to slide down said ways under the action of gravity, and being provided with corresponding stepped recesses affording horizontal supporting, and vertical gripping surfaces.
- 10 15 2. A vise comprising a base, a frame thereon affording oppositely-inclined ways converging toward said base, a jaw mounted to slide on each of said ways, means for simultaneously raising said jaws, the latter, when raised, being free to slide down said ways under the action of gravity.
- 20 25 3. A vise comprising a base, a frame thereon affording oppositely-inclined ways converging toward said base, a jaw mounted to slide on each of said ways, said jaws, when raised, being free to slide down said ways under the action of gravity, and means for simultaneously raising or lowering said jaws.
- 30 35 4. A vise comprising a base, a frame thereon affording oppositely-inclined ways converging toward said base, a jaw mounted to slide on each of said ways, guides for each of said jaws, said jaws, when raised, being free to slide down said ways under the action of gravity, and means for simultaneously raising said jaws.
- 40 45 5. A vise comprising a base, a frame thereon affording oppositely-inclined ways, a jaw mounted to slide on each of said ways, guides for each of said jaws, said jaws, when raised, being free to slide down said ways under the action of gravity, and means pivotally mounted on the vise and associated, but unconnected, with said jaws, for simultaneously raising the same.
- 45 6. A vise comprising a base having parallel side members extending upward there-

from, each of which is provided on its upper side with oppositely-inclined ways, jaws mounted to slide on said ways, each of said jaws being provided with longitudinally-disposed grooves, studs in said side members engaging in said grooves, and means for raising said jaws.

55

7. A vise comprising a base, a frame thereon affording oppositely-inclined ways, a pair of jaws mounted to slide on said ways, said jaws, when raised, being free to slide down said ways under the action of gravity, guides for said jaws, a cradle supporting said jaws at their lower ends, but independent thereof, and means for raising and lowering said cradle.

8. A vise comprising a frame affording oppositely-inclined ways, a pair of self-closing jaws slidably mounted on said ways, guides for said jaws, each of said jaws having on its upper side gripping surfaces and on its under side an outwardly-projecting arm, a cradle mounted to support said jaws at their lower end and having its opposite ends extending over said arms, and means for raising and lowering said cradle.

9. A vise comprising a frame affording oppositely-inclined ways, jaws mounted to slide on said ways, and having gripping surfaces on their upper sides, guides for said jaws, arms projecting outwardly from the under side of each of said jaws, a lever pivotally mounted at one end in said frame, a cradle pivotally mounted on said lever intermediate the ends of the latter, said cradle being adapted to engage the lower ends of said jaws and the upper sides of said arms, whereby when said lever is raised or lowered the jaws may be made to diverge or approach each other respectively.

In testimony whereof I have hereunto set my hand in presence of two subscribing witnesses.

DENNIS PARKS.
